(57) **CLAIM**

The ornamental design for a cart, as shown and described.

DESCRIPTION

FIG. 1 is a perspective view of a cart according to our new design;

FIG. 2 is a perspective view of the cart of FIG. 1 showing a phantomed bin in a shelving channel;

FIG. 3 is a perspective view of the cart of FIG. 1 showing a phantomed refuse container shelf positioned in a shelving channel and a phantomed refuse container hanging from the refuse container shelf;

FIG. 4 is a front view of the cart of FIG. 1;

FIG. 5 is a back view of the cart of FIG. 1;

FIG. 6 is a right side view of the cart of FIG. 1;

FIG. 7 is a left side view of the cart of FIG. 1;

FIG. 8 is a top view of the cart of FIG. 1; and,

FIG. 9 is a bottom view of the cart of FIG. 1.

The ornamental design which is claimed is shown in solid lines in the drawings. Any broken lines in the drawings are for illustrative purposes only and form no part of the claimed design.
